FLASHING

John D. Stebbins, New York, N. Y., assignor to
 Allied Chemical & Dye Corporation, New York,
 N. Y., a corporation of New York

Application April 19, 1945, Serial No. 589,129

4 Claims. (Cl. 108—26)

1

This invention relates to building construction and more particularly to an improved flashing assembly for roofs and the like.

It is an object of the invention to provide an improved ceramic flashing member which may be readily built into walls contiguous to roofs and which cooperates with the roof flashing to form an improved flashing assembly.

It is another object of the invention to provide a flashing member of simple construction which is light in weight, economical to manufacture, and may easily be laid in place of a portion or all of only a single course of bricks in a parapet wall and which, when installed, cooperates with other portions of the wall to provide a recess for the reception of roof flashing.

It is a further object of the invention to provide a flashing assembly of improved appearance and efficiency which eliminates the use of metal in the roof flashing. Other objects and advantages will appear hereinafter.

This invention provides a ceramic flashing member which can be built into a wall involving courses of bricks or other masonry units to form a recess for the reception of flashing and which has substantially the same coefficient of expansion as the masonry units. The flashing member in its preferred embodiment involves a substantially rectangular vitrified clay plate of a thickness materially less than that of the masonry units, which plate is adapted to be embedded in mortar horizontally in the wall with the forward edge of the plate substantially flush with the side of the wall contiguous to the roof, a portion or projection extending downwardly from the forward edge a depth such that, when viewed from its forward edge, the member appears to be of approximately the same thickness as a masonry unit of the wall; and another projection extending downwardly from the plate in spaced relation to the first projection. The projection extending downwardly from the forward edge of the plate cooperates with a portion of the wall below the plate to provide a recess for the reception of flashing and the other projection cooperates with the mortar to hold the member securely in position. The two end edges of the plate are provided respectively with a recess and a complementary portion, so that a plurality of the flashing members may be laid in a course in the place of a portion or all of a single course of masonry units with the recess of one member receiving the complementary portion of an adjacent member. The flashing member may be employed in conjunction with a flashing fender extending from the roof

2

upwardly along the parapet wall over the flashing, the upper edge of the fender being locked in position behind the downwardly-extending projection along the forward edge of the flashing member.

For a more complete understanding of the invention, reference may be had to the accompanying drawing showing, for purposes of exemplification, preferred embodiment of the invention, in which

Figure 1 is a sectional view through a parapet wall and a portion of a contiguous roof provided with one form of flashing assembly of the invention;

Figure 2 is a view in front edge elevation of the flashing member taken in the direction of the arrow 2 in Figure 1;

Figure 3 is a partial sectional view taken along the line 3—3 of Figure 1;

Figure 4 is a view similar to Figure 1, illustrating a somewhat modified form of flashing assembly;

Figure 5 illustrates a further modified form of flashing assembly involving a flashing fender;

Fig. 6 is a plan view of the flashing fender shown in Fig. 5;

Fig. 7 is a view in edge elevation of the flashing fender element illustrated in Fig. 6;

Fig. 8 is a partial cross-sectional view taken on line 8—8 of Fig. 5, illustrating the joint between two flashing fender elements; and

Fig. 9 is a horizontal sectional view illustrating a corner flashing element in position in a parapet wall, the corner element being shown in top plan.

Referring more particularly to Figs. 1 to 3 of the drawing, reference numeral 5 designates generally a roof comprising a roof deck 6 which may be of concrete, wood or other suitable construction covered with a plurality of superposed layers 7 of tar- or asphalt-impregnated felt cemented together with bituminous waterproofing material such as tar, pitch or asphalt, and an overlying layer 8 of waterproofing material, such as coal-tar pitch or asphalt, in which is embedded granular material, e. g. slag or gravel. Contiguous to one edge of the roof is a parapet wall 10 comprising courses of masonry units 11, which may be brick, tile, stone or the like, separated by mortar 12. Located in the angle between the wall and roof is a cant 13, over which one or more plies of the felt roofing 7 extend.

The flashing assembly of the invention involves a ceramic flashing member indicated as a whole by reference numeral 15. The flashing member is

of baked clay construction, being preferably constituted of vitrified clay so that its surfaces are impervious to moisture, and may be made in a manner similar to vitrified brick, employing molds or presses of appropriate shape. The member 15 involves substantially rectangular plate 16 of a thickness materially less than the thickness of masonry units 11, a projection or portion 17 extending downwardly from the forward edge of the plate a depth such that the thickness of the member when viewed edgewise in the direction of arrow 2 is approximately equal to the thickness of masonry units 11, and a projection 18 of about the same length as the plate extending downwardly from the lower surface of the plate in spaced parallel relation to projection 17. The plate may be longer than the individual masonry units, e. g. it may be of a length equal approximately to that of two or more masonry units. In the form shown in the drawing, the plate 16 is of a width such that the flashing member extends only part way through the parapet wall; if desired, the width of the plate may be such that member 15 extends entirely through the wall in place of the entire widthwise extent of a course of masonry units 11. One end edge of the plate is provided with a recess 20 (see Figures 2 and 3) complementary to the opposite end edge portion 21 of the plate, so that the flashing members may be laid in a course with the recess of each member receiving the complementary end portion of an adjacent member. As shown in Figure 1, the major portion of the flashing member is embedded in mortar 12, i. e. the mortar substantially completely surrounds all of the member except its forward edge and a relatively small portion behind projection 17 which provides a recess 22 for the reception of flashing. Projection 18 interlocks with the mortar and aids in securing the flashing member securely in position in the wall. If desired, a plurality of projections 18 spaced at intervals between the front and rear edges of plate 16 may be provided to anchor the flashing member more securely in the wall. Instead of being continuous, projection 18 may be discontinuous, e. g. constituted of one or more lugs of appropriate length to provide suitable anchorage.

As shown in Figure 1, one or more sheets of flashing material 23, e. g. flexible roofing felt impregnated with waterproofing material, such as asphalt, coal-tar or coal-tar pitch, extend from the roof over cant 13 and the roofing material overlying the cant upwardly along the parapet wall and into recess 22. The lower edge of the flashing sheet 23 is covered by and forms a waterproof bond with the layer 8 of waterproofing material and the upper edge of the flashing is cemented in recess 22 by plastic bituminous material 25, such as asphalt, coal-tar pitch, coal-digestion pitch, or cements containing such materials admixed with fibrous materials, such as asbestos. If desired, the rear side of projection 17 may be serrated, as illustrated in Figure 1, to aid in securing the plastic material in the recess. The forward edge portions of the row of bricks 11 may be slantingly cut away, as illustrated at 26, to avoid an abrupt bend in the flashing material 23.

Figure 4 illustrates a somewhat modified form of flashing assembly which differs from that illustrated in Figure 1 chiefly in that the flashing member 15 is so positioned with respect to cant 13 that the flashing material 23 and, if desired, one or more layers of the roofing felt 7 extend in a plane from the roof level within the recess 22

formed between the rear of projection 17 and the mortar 12 in which member 15 is embedded, thus avoiding any bend in the flashing material between the roof surface and the recess.

Figures 5 to 8, inclusive, illustrate a modified form of flashing assembly providing a concealed flashing for roofs comprising a surface of roofing units such as promenade tile units. Referring to Figure 5, roof deck 30 is covered by superposed piles of felt 31 impregnated with waterproofing material such as tar or asphalt alternating with layers of waterproofing material such as coal-tar pitch or asphalt. Above the felt roofing is a promenade tile roof surface 32 set in a layer of Portland cement mortar 34 overlying the felt. The parapet wall 35 involves courses of masonry units 36, 37 set in mortar 38 and a course of vitrified clay flashing members 15 embedded in the mortar. Reference numeral 39 designates a sheet of through flashing, constituted of felt saturated with bituminous material, built into the wall in a manner such that one side of the sheet overlies the rear portion of flashing member 15 and extends to the side of the wall opposite the roof to prevent seepage of moisture down through the wall. Such through flashing may also be incorporated in the forms of the invention shown in Figures 1 and 4 but is preferably dispensed with if the member 15 is of a width sufficient to extend substantially entirely through the wall.

The parapet wall is constructed so that the portion of the wall below the member 15 is of somewhat reduced thickness as compared to the portion above the member. One or more plies of flashing material 40 constituted of felt saturated with waterproofing material extend from the roof upwardly along the wall within the recess behind projection 17 of member 15. The flashing material 40 may be integral with material 31 or may be a separate sheet or sheets of waterproof felt extending a substantial distance out over and forming a waterproof joint with material 31, and may be cemented to the wall by a layer 41 of bituminous cement. A course of flashing fenders 42 illustrated in more detail in Figures 6, 7, and 8, are set in mortar in front of and conceal flashing material 40. It will be observed the fender has dove-tail grooves 43 on one face adapted to interlock with the mortar and a projection 44 along its upper edge, which extends into the recess behind the projection 17 of the flashing member 15, to maintain it securely in position. The flashing fender is preferably of a length approximately equal to that of a plurality, e. g. several, of the masonry units and the end edges of the fender are provided with complementary projections and recesses 45 and 46 which interlock with each other, as shown in Figure 8. The space between the flashing fender and the roof tile is filled by caulking material, such as a mixture of coal-tar pitch or asphalt and fibrous material to provide expansion joint 48.

The dimensions of my flashing member will depend chiefly on the nature of the parapet wall in which it is to be disposed and may, of course, be varied as desired. For a parapet wall made up of standard brick 2" x 4" x 8", I prefer to have the rectangular plate about $\frac{3}{4}$ " thick, about 9" wide, and 24" long, and to have each of the projecting portions extend a distance of about $1\frac{1}{4}$ " from the underside of the plate, so that, when viewed from the front edge, the flashing member appears to be about 2" thick. Thus, my flashing member results in a substantial saving of material as compared with brick or block flash-

ings having flashing grooves, and is lighter in weight and therefore easier to handle than such block or brick flashings.

Fig. 9 illustrates a corner flashing element constructed in accordance with the invention. In this element plate 16 and projections 17, 18 each comprise two portions extending at an angle to each other and are shaped to fit a 90° convex corner. The corner element may overlap and underlap two adjacent flashing elements in the manner shown in Fig. 3. Obviously the corner element may be shaped to fit concave or convex corners of any angularity.

Thus it will be seen the invention provides a flashing member adapted to be embedded in mortar and extend partially or entirely through a parapet wall in place of a portion or all of a single course of bricks, which member involves a vitrified clay plate having extending downwardly therefrom projections which form a flashing recess and lock the member in position in the wall. The flashing member is lighter in weight, more economical to make, and may be laid more easily to provide an improved flashing assembly than prior art flashing elements.

Since certain changes may be made without departing from the scope of the invention, it is intended the above description shall be interpreted as illustrative and not in a limiting sense.

I claim:

1. In combination with a roof and a contiguous wall involving horizontal courses of masonry elements vertically separated by mortar, a ceramic flashing member of substantially the same coefficient of expansion as said elements, consisting of a horizontal plate, extending at least partially through said wall between vertically spaced courses of said elements, and at least one leg integral with and projecting downward from said plate, the major portion of said flashing member being embedded in and surrounded by said mortar, said one leg being continuous along the edge of said plate in proximity to said roof and being laterally spaced from said mortar and masonry elements to form between the leg and said elements a recess for the reception of flashing, flashing extending into said recess and cemented therein by means of bituminous plastic.

2. In combination with a roof and a contiguous wall involving courses of masonry units separated by mortar, a course of vitrified clay flashing members of substantially the same coefficient of expansion as said masonry units forming at least

a portion of one of said courses, each of said members comprising a plate horizontally disposed in said wall between vertically separated courses of said masonry, one edge of said plate extending substantially to the side of said wall adjacent said roof, said plate being of a thickness materially less than the thickness of said masonry units, each member further comprising a portion extending downwardly from said edge of said plate along said side of said wall, and a projection extending downwardly from the lower surface of said plate in spaced relation to said downwardly-extending portion, the major portion of said member including said projection being embedded in and surrounded by said mortar, said downwardly-extending portion of said member cooperating with said wall to form a recess, flashing extending upwardly along said wall into said recess, and a flashing fender extending from said roof upwardly along said wall over said flashing, said flashing fender being provided along the upper edge thereof with a projection extending into said recess and locking the fender in position.

25 3. A ceramic flashing member adapted to be built into a wall as described in claim 1, comprising a plate having a flat upper surface, a downwardly projecting leg perpendicular to said plate extending continuously along one edge thereof, the dimensions of said leg being such that, viewed in vertical cross-section, the leg is substantially longer than it is thick and is substantially shorter than the plate, and at least one additional projection extending downward from said plate and spaced from said leg a distance greater than its distance from the opposite edge of said plate, the plate being free of substantial projections on its under surface in the immediate vicinity of said leg.

40 4. A flashing member as defined in claim 3 shaped to provide a corner element.
